CONTROL SYSTEM

Ramon R. Howe, deceased, late of Milwaukee, Wis., by Charles S. Hegel, administrator, Milwaukee, Wis., assignor to Allis-Chalmers Manufacturing Company, Milwaukee, Wis., a corporation of Delaware

Application October 1, 1934, Serial No. 746,361

5 Claims. (Cl. 80—32)

This invention relates to control systems and particularly to systems for controlling the dynamo electric machines used for tensioning materials being wound upon and unwound from 5 reels or similar winding and unwinding mechanisms.

In systems of the above type, it is often desirable to maintain a predetermined tension on the reeled material. Dynamo electric machines have been mechanically coupled to the 10 reels and utilized to tension the material being reeled by energizing the machines so that one tends to wind the material on the winding reel and the other machine runs as a generator 15 tending to prevent unwinding of the unwinding reel. As the material is wound and unwound the effective diameters of the reels change and hence the tensioning pull transmitted by the machines must change accordingly in order to 20 maintain the tension on the material.

Various mechanisms mechanically actuated by the tension or slack in the reeled material have been utilized to control the excitation of tensioning machines of the above type but these 25 of necessity are either delicate mechanisms that easily get out of working order or if sufficiently rugged are not sufficiently accurate and stable to maintain the tension at the desired value. Such mechanical devices such as rollers actuated 30 by the slack in the strip are physically in the way and are also undesirable due to the fact that they leave a mark on the strip of material.

It is an object of this invention to provide 35 an improved system for controlling the dynamo electric machines in tensioning systems of the above type that avoids the above disadvantages and solves the above problem in an efficient and novel manner.

It is a further object of this invention to provide 40 a tensioning system that is simple, rugged and yet is sufficiently sensitive to maintain a constant tension.

These and other objects and advantages are 45 obtained by this invention, the various novel features of which will be apparent from the drawing and description herein and will be more particularly pointed out in the claims.

As illustrated example of an application of 50 this invention is shown in the accompanying drawing, in which:

Figure 1 is a diagrammatic showing of a tensioning system embodying a form of the invention;

Fig. 2 is an illustration showing one manner

of utilizing the tensioning system shown in Fig. 1 in a strip rolling mill.

Referring to Fig. 2 of the drawing, a strip rolling mill is shown wherein the main drive motor 12 may be mechanically connected to a reel 15 or 16 to pull a strip of material 14 through rolls 17 which perform an operation on the strip. The clutch mechanisms, generally designated as 19 and 20, determine which reel is connected to the main drive motor. Connected to each of the reels 15 and 16 are dynamo electric machines 8 and 9 the field windings of which are oppositely energized so that the forward or winding machine runs as a motor tending to aid the main drive motor. The 15 trailing machine, that is, the machine connected to the unwinding reel, is connected to run as a generator thereby acting as a brake to tension the strip of material between the unwinding reel and the rolls 17. It is the usual 20 practice to reverse the drive, running the strip back and forth through the rolls in order to have several operations performed. Hence upon reversal of the drive, the trailing reel of the 25 last pass becomes the winding reel of the next pass. It is desirable therefore that the tensioning machines 8 and 9 be so connected and so energized and controlled so that the strip may be easily reversed and so that the trailing machine will always supply a predetermined 30 tension to the strip.

If the reel diameters were constant, a constant tension could be applied to the trailing reel by energizing the trailing reel machine so that it would apply a constant torque to the 35 trailing reel. However, as the trailing reel unwinds the effective reel diameter decreases and hence the lever arm through which the braking torque is transmitted from the reel to the strip is shortened and the braking torque of the 40 trailing machine must decrease accordingly, in order to maintain the tension at the desired value.

In Fig. 1 there is shown a control system in which the strip direction may be easily reversed 45 and in which the trailing tensioning machine will maintain a constant back pull on the strip. The main drive motor 12 is energized by a generator 6 which is driven by synchronous motor 5 which also drives an auxiliary generator 7. 50 The synchronous motor 5 is energized from the alternating current source 40. The tensioning machines 8 and 9 have their armatures connected in series across the terminals of the auxiliary generator 7. The field windings 28 55

and 29 of the back tension machines are oppositely connected in parallel to the direct current source 41, so that one machine will run as a motor while the other runs as a generator. The 5 parallel field windings are connected in series with the resistance 33 of a differential regulator generally designated as 32 which has a contact 34 actuated by solenoids 35 and 36. The coils 35 and 36 are responsive to the voltages across 10 the machines 8 and 9 respectively and movement of the contact 34 acts to increase the field current of one machine and simultaneously decrease the field current of the other machine.

To consider the operation of the system the 15 strip is considered to be moving in the arrow direction, the clutch 26 coupling the main drive motor 12 to the reel 16 which will be the winding reel. As the mill is brought up to any desired speed by manipulation of the rheostat 37, 20 a constant horsepower input to the motor 12 is maintained by the regulator generally designated as 13. As the current in the armature circuit of the main motor tends to increase with the building up of the strip on the reel 16 the 25 regulator 13 is operated to increase the current in the field winding 22 thus tending to decrease the motor armature current and maintain it constant. With constant horsepower input and the increasing torque requirement due to the 30 building up of the material on the reel 16, the speed of the main motor 12 decreases directly as the diameter of the reel 16 increases. The speed of the reel 16 and motor 9 likewise decreases as they are mechanically connected to the motor 35 12. However, the lineal strip speed remains constant as the decrease in the speed of the reel 16 is compensated by the building up of the strip on the reel.

As the speed of the machine 9 decreases its 40 counter-E. M. F. decreases. However, as the size of this machine is generally one-tenth that of the main driving motor, this change has little effect upon the mill drive. The trailing machine 8 is pulled by the strip of material and because of 45 the energization of its field 28 it runs as a generator supplying a torque to the reel 15 and thereby supplying the desired tension to the strip of material. As the strip of material unwinds from the reel 15, the machine 8 increases its speed in 50 direct proportion to the diameter of the reel 16. As the speed of machine 8 increases, the generated E. M. F. across its terminals increases. These changes in the machine voltages, that is, the decrease in voltage across the machine 9 and the 55 increase in voltage across the machine 8, act on coils 35 and 36 to move the contact 34 to the right as viewed in the drawing. This will decrease the energization of field winding 28 and increase the energization of the field winding 29 60 until the machine voltages are again equal. Thus, the flux of each machine is varied in direct proportion to the reel diameter change and the torque supplied by the trailing machine decreases as the speed increases, that is, in proportion to 65 the reel diameter change. The desired value of tension is thus maintained throughout the pass.

As the effective voltage across the winding machine is the generated voltage minus the IR drop and the effective voltage across the trailing machine is the generated voltage plus the IR drop, this difference must be compensated in any suitable manner. Upon reversal of the generator field 26 by the switch 24 the mill runs in the opposite direction, the main motor 12 being con-

nected to reel 15 by the clutch 19, the clutch 20 now being in the position shown. The machine 9 then runs as a generator and in the same manner as above shown supplies a constant tension to the strip 14.

5

Although only one embodiment of the present invention has been illustrated and described, it will be apparent to those skilled in the art that various changes and modifications may be made therein without departing from the spirit of the 10 invention or from the scope of the appended claims.

It is claimed and desired to secure by Letters Patent:

1. In combination, a pair of reels adapted to be 15 joined by a length of material, dynamo electric machines connected to each of said reels, a source of current supply connecting the armatures of said dynamo machines in series and means connected so as to be responsive to the voltages across 20 said dynamo machines for simultaneously regulating the excitation of said dynamo machines.

2. In combination, a pair of reels adapted to be 25 joined by a length of material, dynamo electric machines connected to each of said reels, a source of electric energy, means for connecting the armatures of said dynamo electric machines in series with said source, means for oppositely connecting the field windings of said dynamo electric machines in parallel and means responsive 30 to the voltage across each of said dynamo electric machines for regulating the current in one of said field windings inversely with respect to the current in the other of said field windings.

3. In combination, a pair of reels adapted to be 35 joined by a length of material, dynamo electric machines connected to each of said reels, a source of electric energy, means for connecting the armatures of said dynamo electric machines in series with said source, regulating means responsive 40 to the voltages across said machines for controlling the field windings of said dynamo electric machines whereby a substantially constant tension is maintained on said length of material.

4. A tension regulator comprising a pair of 45 reels adapted to be joined by a length of material, dynamo electric machines connected to each of said reels, a source of electric energy, means for connecting the armatures of said dynamo electric machines in series with said source, means 50 for connecting the field windings of said dynamo electric machines oppositely in parallel and means for regulating the current in said field windings whereby a substantially constant tension is maintained on said material, said regulating means 55 comprising a differential rheostat responsive to the voltages across said dynamo electric machines.

5. In combination, a pair of spaced reels adapted to be joined by a strip of material, dynamo 60 electric machines connected to each of said reels, a source of electric energy, means connecting the armatures of said dynamo electric machines in series with said source, means connecting the field windings of said dynamo electric machines 65 oppositely in parallel, a field winding regulator connected so as to be responsive to the difference in voltages across said machines, and means connecting said regulator to said field windings so that both said windings are regulated simultaneously.
